UNITED STATES PATENT OFFICE.

WALTER EVERETT MOLINS, OF LONDON, ENGLAND.

MACHINE FOR APPLYING STAMPS, LABELS, AND THE LIKE.

Application filed March 6, 1923, Serial No. 623,264, and in Great Britain April 3, 1922.

This invention relates to an improved machine for applying stamps, labels and the like, to a series of packets or the like fed thereto.

5 Machines are already known in which stamps are cut from a sheet or strip or fed singly and delivered to a gumming or damping device and then pressed on to the packets, the latter being fed continuously to the 10 machine in some cases.

The present invention consists in the provision of improved means for dealing with the stamp or the like after same has been delivered to the machine whereby the stamp is supplied with adhesive and pressed on a packet without checking the travel of the packet through the machine.

Any suitable known feeding means may be employed for feeding the stamps continuously to the machine from a magazine.

For example the stamps may be supplied to the machine singly from a magazine and fed therefrom by a suction feed device or they may be supplied in a continuous strip 25 and cut therefrom by a suitable cutting device.

The articles are fed continuously to the machine in any desired manner and a drying apparatus may be combined with the 30 machine to dry the stamps after application to the articles.

The invention is particularly, but not exclusively, adapted for use in applying stamps to or over the ends of cigarette or tobacco 35 packets and a machine suitable for this purpose will now be described, but it will be understood that the machine may be used for applying stamps, labels, or the like to articles other than those specified.

40 To enable the invention to be fully understood it will now be described by reference to the accompanying drawings in which:

Figs. 1 and 2 are views of packets showing the forms of stamp applied thereto, and

45 Fig. 3 is a part sectional side elevation of one form of a machine adapted to apply the stamp shown in Fig. 1 constructed according to the invention;

50 Fig. 3^a is a detail plan view of a detail of the gumming roller and stamp drum of the machine shown in Fig. 3;

Fig. 3^b is a part sectional side elevation drawn to a larger scale of a portion of Fig. 3 showing a stamp being delivered, the gum wheel and parts being omitted. 55

Fig. 3^c is a view similar to Fig. 3^b with the parts in a different position;

Fig. 3^d is a side view of Fig. 3^b;

Fig. 3^e is a plan view of a detail showing the mounting of the suction tubes; 60

Fig. 4 is a plan view of the stamping channel thereof;

Figs. 4^a and 4^b are details of the method of delivering the stamp to the stamp drum;

Figs. 5 and 6 are plan and elevation respectively of a detail of the machine, and 65

Figs. 7 and 8 are views illustrating the application of the stamp to the packet.

Fig. 9 is a back view of the machine shown in Fig. 3, showing the feeding driving and 70 cut out gear used.

Fig. 9^a is a view of a detail showing the cam for operating the detector mechanism;

Fig. 10 is a view showing a method of operating a heater plate. 75

As shown in Fig. 3 the machine illustrated is adapted to operate on stamps drawn one by one from a pile in a magazine and fed to the machine by a suction device, but it will be understood that the method of feeding 80 the stamps to the machine is not an essential part of the present invention, since the stamps might be cut from a continuous strip.

In the present example, the stamps are 85 piled in a magazine 56 and are withdrawn one at a time by a suction tube 57 connected by a flexible pipe 57^a with an exhauster 94^a on the back of the machine (Fig. 9) and delivered to a rotating feed roller 58 provided with a projecting pin 58^a which engages the back end of a stamp R as best shown in Figures 4^a and 4^b.

An oscillating roller 59 on one arm of a bell crank lever 60 makes contact with the 95 feed roller at the correct time and feeds the stamp down on to the drum 27.

As shown in Fig. 3^b the circumferentially slotted drum 27 is formed with slots 26^a, the portions between the slots having small 100 notches 28 for holding the forward edges of the stamps, forming a comb across the drum.

Guards 27^a are arranged around a portion of the circumference of the drum 27 and a grooved gumming roller 29 rotating in a bath 30 and having an adjustable scraper 31 5 is arranged so that the flanges of the grooves extend into the spaces between the guards 27^a and apply gum in a series of parallel lines to stamps carried on the stamp drum 27. The gumming arrangement is prefer- 10 ably such that the flanges on the gumming roller 29 co-operate with the grooves in the drum 27 and therefore do not apply gum unless the grooves are covered by a stamp.

The oscillating roller 59 on one arm of 15 the bell crank lever 60 makes contact with the feed roller 58 at the correct time and feeds the stamp down on to the drum 27 (Figures 3^b and 3^c), the guard 61 keeping the stamp in its proper track. The stamp is 20 thus held by the projecting pin 58^a on the roller 58 and by the notches 28 on the drum 27. This feeding operation is shown in Figures 4^a and 4^b.

The suction tubes 57 are linked to the 25 other arm of the bell crank lever 60 by a link 100 and the lever is attached to a spindle 60^a passing through the machine frame. The tubes 57 are also linked to a pin 101 on the frame about which they oscillate, (Fig. 3^e). 30 The spindle 60^a is rocked by a lever 92 and roller 92^a engaging a cam 91 on the spindle 120 of feed roller 58 at the back of the machine (Figs. 3^d and 9), so operating the suction tubes 57 and roller 59 through the bell 35 crank lever 60. A spring *d* (Fig. 3^b) returns the linkwork and stop screw *d'* is provided for limiting the up position of the suction tubes.

On one side of the stamp drum 27 is a 40 spindle 62^a carrying two cams 62, 63. A bell crank lever 64 pivoted at 65 carries a roller 66 which engages cam 62 under the action of a spring 67. The lever 64 is grooved and a stamp finger 68 slides therein 45 (Fig. 5). The forward end 68^a of the finger 68 is slotted to pass into the slots in the stamp drum 27 and has depending portions *k*. The finger is reciprocated horizontally by a fork 69 pivoted at 70 engaging a pin 71 on the finger and engaging the cam 63 (Fig. 3). A tension spring 72 returns the finger to its normal position. The bell crank lever 64 is also provided with a depending portion *m*.

55 The packets *c* are delivered from a packetting machine or by hand to a plate 53, arranged adjacent to conveying chains 47 driven by sprockets 49 and supported on idlers 50, 51, the chains carrying conveyor 60 pieces 48. The plate 53 is cut away to allow a piece 48 to pass through same carrying a packet with it. The conveyor pieces 48 are pivotally mounted on the chains and the portion 48^a is supported on a guide rail 53' during 65 their travel on the upper side of the

machine. A spring controlled hinged guide flap 55 is mounted as shown to hold the packets in position on the moving conveyor pieces.

A detector 73 is provided beneath which 70 the packets pass as they are carried on the conveyor before reaching the stamping mechanism.

This detector comprises a plate 73 mounted above the path of the packet and 75 carried by a lever 106 in the back of the machine. One end of this lever is slotted and engages the spindle 104 of sprocket wheel 50. A cam 87^a is mounted on the spindle 104 (Fig. 9^a). A spring 107 pulls lever 106 80 downwards. The cam 87^a engages a roller 108 on the lever. When a packet is beneath the plate 73 no movement of the lever occurs, since the latter cannot fall as the plate is supported by the packet. As the packet 85 leaves the plate 73 for stamping the high part of the cam 87^a still prevents movement of the lever. A stamp has to travel some distance from the magazine to the 90 packet stamping position and the time taken for this journey is the same as that taken by a packet travelling from the detector to the stamping position. The cam 87^a is so arranged that it prevents movement of the lever 106 during the travel of a packet from 95 the detector to the stamping position. If at the moment when a packet arrives at the stamping position a succeeding packet has not engaged the detector, the recessed portion of the cam 87^a will be beneath the roller 108 and since the plate 73 is unsupported, it 100 will drop, the roller 108 falling into the recessed portion of the cam. The lever 106 is connected by a link 108^a to a relief valve 94 on the exhauster 94^a, so that when the 105 lever 106 and roller 107 fall the link 108^a is operated to open the valve 94. This breaks the vacuum in the exhauster and so breaks the suction at the stamp feeding device and prevents the feeding of a stamp.

110 After passing the detector 73, the packet passes beneath a plate 73^a attached to the underside of the gum bath 30 and into the stamping channel over the plate 53 and beneath the stamping mechanism. The sides 115 53^a, 53^b, of this channel are yielding and held in position by screws passing through spacing washers and into the edges of plate 53 so that they touch the sides of the packet as it receives the stamp (Fig. 3). The packet is carried into the channel 53 under the drum 27 and a gummed stamp *o* is delivered 120 on to the centre of the end of the packet so that it overlaps, (Fig. 1).

125 As it is applied, the finger 68 descends through the slots in drum 27 removing the stamp and dropping thereon as shown in Fig. 7, the depending portion *k* of said finger pressing the projecting end of the stamp against the leading side of the packet *r*, 130

Figs. 7 and 8, the finger receiving its reciprocating motion to press the stamp firmly against the side of the packet.

At the same time the end *m* of the bell crank lever 64 is dealing with the rear end of a stamp on the packet *s* (Fig. 7).

The packet *r* is still being moved by the conveyor piece, but packet *s* is stationary and consequently the packets close up as shown 10 in Fig. 8.

The finger 68 is then moved back by its cam and slotted link and clears the newly stamped packet. When this occurs the bell crank lever 64 is lifted up and the packet 15 *r* comes into contact with *s* thus holding the stamps in position until they are dried. The bell crank 64 and finger 68 descend again with the end *m* of lever 64 touching the rear of packet *r* and the finger 68 engaging the stamp of a fresh packet.

In Fig. 8 the finger 68 is shown resting on the top of the packet and about to press the leading end of the stamp *o* against the leading side of the packet, the previous packet being operated on and finished by the lever 64.

The sealed and stamped packet passes on and at the point where the conveyor pieces 48 turn over, spring clips 74 (Fig. 3) are 30 provided for holding up the packet as the conveyor piece leaves it.

By the time the lever 64 and finger 68 have finished a packet and become disengaged therefrom another packet is almost 35 in position to be operated on. Thus a group of packets as at 75 is always in the channel, and is constantly moved forward as a new packet arrives at the stamping position.

As the packets move up the channel the 40 tops of the packets and the stamps are controlled by a narrow strip 76 which is either screwed to the frame, as at 77, or carried by the stamp guide, as shown in chain lines at 78. The lower part of the bell chank lever 45 64 is recessed to avoid interference with the strip 76.

The stamped packets then pass beneath the plate 95 heated by electric or other means at 96 and the dried packets are removed 50 from the end of the channel.

Preferably the plate 95 is pivoted on a pin 97 at the back of the machine frame and actuated by a cam 98 and lever 99 (Fig. 10). It is thus moved up and down in such 55 manner that the plate is "up" when the packets are moved along by the entry of another packet into the channel.

The machine may be driven by any suitable means and as here shown the drive is 60 applied to the spindle 104 of sprocket wheel 50 and on the spindle at the back of the machine a sprocket wheel 110 is fixed which is geared by a chain 111 to sprocket wheels 112, 113, 114, respectively on the spindles 65 of the stamp drum 27, gum wheel 29, and

spindle 62. The stamp feed roller 58 is driven by a gear wheel 115 on its spindle 120 gearing with a wheel on the spindle of the stamp drum 27. The exhauster 94 is driven as shown by an eccentric 94^b on the spindle 120. An idler 121 is provided for taking up the slack in the chain. Obviously the various spindles may be driven by toothed gearing if desired.

It will be understood that the machine 75 may be used to apply a stamp across the end of the packet and down over one of the adjacent sides only.

Further, machines such as hereinbefore described may be arranged to apply stamps 80 in any desired position on the packets and to operate with any suitable known form of delivery means for the stamps.

Having thus described the nature of my 85 said invention and the best means I know of carrying the same into practical effect, I claim:

1. In an automatic machine for applying stamps and labels in combination, a magazine, means for delivering a stamp from the 90 magazine, a circumferentially slotted rotary member for receiving the stamp having means for positively holding the stamp thereon against slipping and a gumming roller having projections fitting into the 95 slots of the rotary member for applying adhesive to the stamp thereon.

2. In an automatic machine for applying stamps and labels in combination, a magazine, means for delivering a stamp from the 100 magazine, a circumferentially slotted rotary member for receiving the stamp said member having notched portions between the slots for positively engaging one edge of the stamp, and a gumming roller having projections fitting into the slots of the rotary member 105 for applying adhesive to the stamp thereon.

3. In an automatic machine for applying stamps and labels in combination, a magazine, means for delivering a stamp from the 110 magazine, a circumferentially slotted rotary member for receiving the stamp said member having notched portions between the slots for positively engaging one edge of the stamp, a gumming roller having projections fitting into the slots of the rotary member 115 for applying adhesive to the stamp thereon and means for removing the gummed stamp from the rotary member and pressing it on 120 the desired article.

4. In an automatic machine for applying stamps and labels in combination, a magazine, means for delivering a stamp from the 125 magazine, a circumferentially slotted drum for receiving the stamp, a feed roller for delivering the stamp on to the drum, a pin on the feed roller for engaging one edge of the stamp, a gumming roller having projections fitting into the slots of the drum for apply- 130

ing adhesive to the stamp on the drum and means for removing the gummed stamp from the drum and pressing it on a desired article.

5. In an automatic machine for applying 5 stamps and labels in combination, a magazine, means for delivering a stamp from the magazine, a circumferentially slotted drum for receiving the stamp, a gumming roller having projections fitting into the slots of the drum for applying adhesive to the stamp and means for removing the gummed stamp from the drum and applying it to the end of packet and over two opposite sides thereof.

6. In an automatic machine for applying 15 stamps and labels in combination, a magazine, means for delivering a stamp from the magazine, a circumferentially slotted drum for receiving the stamp, a gumming roller having projections fitting into the slots of the drum for applying adhesive to the stamp on the drum, a slotted presser finger having a depending portion and means for reciprocating the finger through the slots in the drum to detach a gummed stamp and to 20 press same into contact with a packet across the end and down one of the two opposite sides and a second reciprocating presser finger having a depending portion for pressing the stamp into contact with the other opposite side of the packet.

7. In an automatic machine for applying stamps and labels in combination, a magazine, means for delivering a stamp from the magazine, a circumferentially slotted drum 35 for receiving the stamp, means for pressing each stamp on to the drum as it is received from the magazine, a gumming roller having projections fitting into the slots of the drum for applying adhesive to the stamp on the drum, a slotted presser finger having a depending portion and means for reciprocating the finger through the slots in the drum, to detach a gummed stamp and to press same into contact with a packet across the end and 40 down one of the two opposite sides thereof and a second reciprocating presser finger having a depending portion for pressing the stamp into contact with the other opposite side of the packet.

50 8. In an automatic machine for applying stamps and labels in combination, a magazine adapted to contain a pile of stamps, suction means for delivering a stamp from the magazine, a circumferentially slotted rotary member for receiving the stamp having notched portions between the slots for positively engaging one edge of the stamp and a gumming roller having projections fitting into the slots of the rotary member for applying adhesive to the stamp thereon.

9. In an automatic machine for applying stamps and labels in combination, a magazine adapted to contain a pile of stamps, suction means for delivering a stamp from the magazine, a circumferentially slotted ro-

tary member for receiving the stamp having notch portions between the slots for positively engaging one edge of the stamp, a gumming roller having projections fitting into the slots of the rotary member for applying adhesive to the stamp thereon and means for removing the gummed stamp from the rotary member and pressing it on a desired article.

10. In an automatic machine for applying 75 stamps and labels in combination, a magazine adapted to contain a pile of stamps, suction means for delivering a stamp from the magazine, a circumferentially slotted drum for receiving the stamp, 80 a gumming roller having projections fitting into the slots of the drum for applying adhesive to the stamp on the drum, a slotted presser finger having a depending portion and means for reciprocating the finger 85 through the slots in the drum, to detach a gummed stamp and to press same into contact with a packet across the end and down one of the two opposite sides thereof and a second reciprocating presser finger having a 90 depending portion for pressing the stamp into contact with the other opposite side of the packet.

11. In an automatic machine for applying stamps and labels in combination, a magazine adapted to contain a pile of stamps, suction means for delivering a stamp from the magazine, a circumferentially slotted drum for receiving the stamp, means for pressing each stamp on to the drum as it 100 is received from the magazine, a gumming roller having projections fitting into the slots of the drum for applying adhesive to the stamp on the drum and a slotted presser finger having a depending portion and means for reciprocating the finger through the slots in the drum, to detach a gummed stamp and to press same into contact with a packet across the end and down one of the 105 two opposite sides thereof and a second reciprocating presser finger having a depending portion for pressing the stamp into contact with the other opposite side of the packet.

12. In an automatic machine for applying 110 stamps and labels in combination, a magazine, means for delivering a stamp from the magazine, a circumferentially slotted drum for receiving the stamp, a gumming roller having projections fitting into the slots of the drum for applying adhesive to the stamp on the drum, an endless conveyor for carrying packets into and out of the stamping position and a discharge channel having a heated wall.

13. In an automatic machine for applying 115 stamps and labels in combination, a magazine, means for delivering a stamp from the magazine, a circumferentially slotted drum for receiving the stamp, a gumming roller 120

- having projections fitting into the slots of the drum, a slotted presser finger having a depending portion, means for reciprocating the finger through the slots in the drum, a 5 second reciprocating presser finger having a depending portion, an endless conveyor for carrying packets into and out of the stamping position and a discharge channel for the conveyor.
- 10 14. In an automatic machine for applying stamps and labels in combination, a magazine, means for delivering a stamp from the magazine, a circumferentially slotted drum for receiving the stamp, a gumming roller having projections fitting into the slots of the drum, means for removing a gummed stamp from the drum and applying it to a 15 packet, an endless conveyor for carrying packets and means operated by the passage 20 of a packet to be stamped for stopping the feed of a stamp unless a packet is in the stamping position.
15. In an automatic machine for applying stamps and labels in combination, a magazine, means for delivering a stamp from the 25 magazine, a circumferentially slotted drum
- for receiving the stamp, a gumming roller having projections fitting into the slots of the drum for applying adhesive to the stamp on the drum, an endless conveyor for carrying packets into and out of the stamping position, a discharge channel having a heated wall and means for raising and lowering the heated wall as packets are passed into the channel. 30
16. In an automatic machine for applying stamps and labels in combination, a magazine adapted to contain a pile of stamps, suction means for delivering a stamp from the magazine, a rotating feed roller for receiving the stamps from the suction means, a pin on said roller engaging the back end of a stamp, a circumferentially slotted drum for receiving the stamp, a gumming roller having projections fitting into the slots of the drum, means for removing a gummed stamp from the drum and applying it to a 35 packet, and an endless belt conveyor for packets to be stamped. 40

In testimony whereof I have signed my name to this specification. 45

WALTER EVERETT MOLINS.
